UNITED STATES PATENT OFFICE.

CHARLES W. MORDEN, OF PORTLAND, OREGON.

LATCH FOR FOOT-LEVERS.

Specification of Letters Patent. Patented Apr. 11, 1916.

1,178,816.

Application filed August 27, 1914. Serial No. 858,964.

To all whom it may concern:

Be it known that I, CHARLES W. MORDEN, a citizen of the United States, and a resident of the city of Portland, county of 5 Multnomah, State of Oregon, have invented a certain new and useful Improvement in Latches for Foot-Levers, of which the following is a specification.

My invention relates to the foot pedals 10 provided on automobiles, for example, and has for its purpose to provide means whereby the foot pedal may be temporarily locked in place after having been operated.

I have illustrated the utility of my invention as applied to the pedal or foot lever of speed changing mechanisms of the Ford automobile, and said pedal, when it is moved into its forward position, and so held, causes the low speed gears to operate; and 15 it will be seen my invention, in a general way, consists in combining with the spring-controlled foot lever a latch, preferably pivoted in place, adapted for being engaged with said foot lever, and the latch being 20 so arranged as to be operable by the foot operating said foot lever, and means adapted to normally hold said latch out of the path 25 of motion of said foot lever.

The details of my invention are herein- 30 after fully described, reference being had to the accompanying drawings, in which:

Figure 1 shows a section of the dash- 35 board of a Ford automobile, and shows a shaft of the speed changing mechanism and a foot lever or pedal mounted on such shaft and held in its normal position by a spring, and my invention is shown as applied for holding the foot lever in its forward position in which it is shown in dotted outline;

40 Fig. 2 is a front elevation of the parts shown in Fig. 1; Fig. 3 is a detail of the bracket fastened to the dash-board of the automobile and on which bracket my latch is pivotally supported; Fig. 4 is a detail of the 45 latch; Figs. 5, 6 and 7 are details of construction which enter into my latch when all the parts are assembled, as shown in the sectional view Fig. 8; and Fig. 9 shows a different type of latch which may be substituted in place of the latch shown in Fig. 4, where it is desired to provide means for holding the pedal in two positions instead 50 of only one position.

a represents the foot-board of an auto- 55 mobile, *b* the dash-board, and *c* the slot in which the foot lever or pedal, *d*, mounted

on the shaft, *e*, of the speed changing mechanism operates, said pedal, *d*, being controlled and held in its normal position by the spring *f*. 60

g is a part of the steering post. On the base *g'* of the steering post is mounted the bracket part *h* of my latch. A detail of this part is shown in Fig. 3. It is made with slots *i*, through which the steering- 65 post base-bolts *j* are inserted. The sole *h'* of the bracket has a slot *k*. The pivot bolt, *l*, is made with a head and square shank so that it may be longitudinally moved in the slot *k* of the sole *h'*, but cannot rotate 70 therein. Over the bolt *l*, is placed a sleeve *m* which serves as a spacing member. On the sleeve is rotatably mounted the latch *n*. Over the sleeve *m* and on the pivot bolt *l* is placed a cap *o*, secured in place by a 75 nut *p* seated on a washer *p'*. The latch *n* is made with perforation *n'*, and the cap *o* is made with a series of perforations *o'*. A top view and a view of the under side of the cap *o* is shown in Figs. 6 and 7. Said 80 perforations receive the ends of a coil-spring *q*, shown in plan and side elevations in Fig. 5. The spring *q* is so arranged as to cause the lug *n''* of the latch *n*, which projects through the aperture *o''* of the cap 85 *o*, to be held against the stop *r* of the cap *o*, thereby so positioning the latch *n* as to clear the path of motion of the pedal or foot lever *d*. As evident, by shifting the end of the spring *q*, engaged with one of the holes 90 *o'* of the cap *o*, from one to the other of said series of holes *o'*, the spring tension 95 may be adjusted as desired.

m' represents a felt oil-pad to keep lubricant on the pivot member. 95

As shown in Fig. 4, the latch has a short member *n''* and a long member *n'*. The short member *n''* is provided with an inwardly projecting hook *t* and the long member *n'* is provided with a heel plate *c*. The latter enables the operator of the automobile to throw the latch into engagement with the pedal *d* by the heel of the same foot which he uses in operating said pedal. When the pedal *d* is so engaged the tension of the 100 spring *f* will hold the same in engagement with the hook *t* of the latch. To release the latter a slight movement forward of the pedal *d* is all that is required, whereupon the spring *q* will act to restore the latch to 105 its normal position.

In Fig. 9 I have shown a latch *w*, which

may be substituted in place of the latch *n*. It is in all respects the equivalent of the latter, but has this additional feature: That instead of having but a single toe as *t*, it 5 has two toes *w*, *w*², so that the pedal *d* may be held in two different positions, instead of only in one position, as by the use of the latch shown in Fig. 4.

The purpose of providing the slot *k* in 10 the sole of the bracket *h* is to arrange for the adjustment of the latch *n* toward and from the pedal *d*, and thus into proper co-operative relation therewith. In this connection it is also to be noted that the devices which control the pedal, exclusive of 15 the support bracket, are arranged in the form of a unit; that is to say, when the nut *p* of the bolt, *l*, is loosened, the latch *n* and cap *o*, being connected by the spring *q*, 20 may be moved together both longitudinally and radially in order to bring the latch into proper co-operative relation with the pedal.

I claim:

1. The combination with a spring-controlled foot lever, of a pivoted latch of V-shaped form its members straddling the path of motion of said foot lever, said latch being so arranged as to be operable by the heel of the foot operating said foot lever; 25 and means adapted to normally hold said latch clear of the path of motion of said foot lever.

2. The combination with a foot lever of 30 an automobile, of a fixed support, a bifurcated latch pivoted thereon, the members of said latch straddling the path of motion of said foot lever, one member of such latch being provided with an inwardly projecting lug, the other member being of greater 35 length and adapted for being operated by the foot operating the foot lever, a stop limiting the motion of the latch, and a spring controlling said latch and normally so positioning the same that its members 40 straddle the path of motion of the foot lever.

3. The combination with a foot lever of 45 an automobile, of a fixed support, a bifurcated latch pivoted thereon, the members of said latch straddling the path of motion of said foot lever, one member of such latch being provided with an inwardly projecting lug, the other member being of greater 50 length and provided with a heel-plate whereby the latch is adapted for being operated by the foot operating the foot lever, a stop limiting the motion of the latch, and a spring controlling said latch and normally so positioning the same that its members 55 straddle the path of motion of the foot lever.

4. The combination with a foot lever of 60 an automobile, of a fixed support, a bifurcated latch pivoted thereon, the members of said latch straddling the path of motion of

said foot lever, one member of such latch being provided with an inwardly projecting lug, the other member being of greater length and adapted for being operated by the foot operating the foot lever.

5. The combination with a foot lever of 70 an automobile, of a fixed support, a bifurcated latch pivoted thereon, the members of said latch straddling the path of motion of said foot lever, one member of such latch being provided with an inwardly projecting lug, the other member being of greater 75 length and adapted for being operated by the foot operating the foot lever, and a spring controlling said latch and normally so positioning the same that its members 80 straddle the path of motion of the foot lever.

6. The combination with a foot lever of 85 an automobile, of a fixed support, a bifurcated latch pivoted thereon, the members of said latch straddling the path of motion of said foot lever, one member of such latch being provided with an inwardly projecting lug, the other member being of greater 90 length and adapted for being operated by the foot operating the foot lever, a spring controlling said latch and normally so positioning the same that its members 95 straddle the path of motion of the foot lever, and the latch and controlling spring thereof being adjustable as a unit.

7. The combination with a foot lever of 100 an automobile, of a fixed support, a pivot bolt carried by the latter, a cap secured by the pivot bolt, a spacing element spacing the cap from said support, a latch rotating about the spacing element, said latch being of V-shaped form, and its members straddling the path of motion of the foot lever, one member of the latch being adapted to 105 be engaged with the foot lever, a stop limiting the rotation of the latch, and a spring operating to hold the latch against said stop whereby its members will be positioned to clear the path of motion of said foot lever.

8. The combination with a foot lever of 110 an automobile, of a fixed support, a pivot bolt carried by the latter, a cap secured by the pivot bolt, a spacing element spacing the cap from said support, a latch rotating about the spacing element, said latch being of V-shaped form, and its members straddling the path of motion of the foot lever, one member of the latch being adapted to 115 be engaged with the foot lever, a stop limiting the rotation of the latch, and an adjustable spring operating to hold the latch against said stop whereby its members will be positioned to clear the path of motion of 120 said foot lever.

9. The combination with a foot lever of 125 an automobile, of a fixed support, a pivot bolt carried by the latter, a cap secured by the pivot bolt, a spacing element spacing the cap from said support, a latch rotating about the spacing element, said latch being of V-shaped form, and its members straddling the path of motion of the foot lever, one member of the latch being adapted to be engaged with the foot lever, a stop limiting the rotation of the latch, and an adjustable spring operating to hold the latch against said stop whereby its members will be positioned to clear the path of motion of 130 said foot lever.

the cap from said support, a latch rotating about the spacing element, said latch being of V-shaped form, and its members straddling the path of motion of the foot lever, **6** one member of the latch being adapted to be engaged with the foot lever, a stop limiting the rotation of the latch, and a spring, one end of which is fastened to the latch

and the other to the cap, operating to hold the latch against said stop whereby its members will be positioned to clear the path of motion of said foot lever. **10**
